LINING STRUCTURE FOR ROTARY CRUSHERS

Stanley D. Hartshorn, Wayne, Pa., assignor to Pennsylvania Crusher Company, Philadelphia, Pa., a corporation of New York

Application March 23, 1948, Serial No. 16,439

5 Claims. (Cl. 241—91)

1

This invention relates to crushers and particularly to the type known as the Bradford breakers employing a rotatable cylinder having shelves or the like for stirring and lifting material.

It is an object of this invention to provide the crushing chamber with means adapted to handle a wide range of sizes of the material, and in particular to provide for operation with relatively large sizes effectively and without injury to the apparatus.

A further object of the invention, particularly in the special structure of the members within the crushing chamber will appear from the following specification taken in connection with the accompanying drawings in which:

Fig. 1 is a developed view of a "Bradford" breaker embodying this invention;

Fig. 2 is a sectional view of a "Bradford" breaker embodying this invention; and

Fig. 3 is a perspective view of the interior of a "Bradford" breaker showing a modification of one feature of this invention.

In Fig. 1 a "Bradford" type breaker has a cylinder or drum 10 made up of a suitable frame and a foraminous wall mounted for rotation. The frames 11 and 12 at the respective ends of the drum 10 consist of circular members of frustoconical form having outer tires 13 and 14 respectively carried on wheels 15. The cone 11 at the left end of the drum 10 as seen in Fig. 1 is the feed cone and the cone 12 at the right end of the drum 10 is the discharge cone. The discharge cone 12 is exteriorly provided with a sprocket (not shown) through which the drum 10 is driven by a roller chain from a speed reducer (not shown) or the drum 10 may be driven by any other suitable means.

Connecting the frames 11 and 12 are a series of beams 19 and the wall of the drum 10 may be made up of foraminous plates 21 having surfaces 43 preferably lapped at their points of engagement and bolted or otherwise secured to each other and to said beams 19. The interior of the breaker drum 10 is provided with a series of lifting shelves 22 which serve to carry the material undergoing treatment during the rotation of the drum upward so that it may be dropped and broken by impact against the plates 21. Intermediate the shelves 22 are a series of deflector blades 23 arranged to progressively divert the material undergoing reduction and carry it from the feed cone 11 to the discharge cone 12 so that while those portions of the treated material that are reduced to fragments of the intended size and smaller pass through the apertures 24 in the

2

foraminous plate sections 21, the unreduced material is carried to the discharge cone 12.

The lifting shelves 22 are shown in sections which consist of a base portion 25 with a laterally extending flange 26 which is stepped longitudinally of the cylinder as illustrated in Fig. 1. The stepping provides a plurality of inclined surfaces 27 which terminate in end walls 28. The stepped portions are inclined in three directions, inwardly and downwardly with respect to the radial plane and the direction of rotation of the drum as shown by the radial line I—I in Fig. 2 and are also inclined from the feed end toward the discharge end of the drum 10 as illustrated in Fig. 1. Thus, the material that is picked up by the lifting shelves 22 will be moved along the drum 10 by the shelves 22 so that the material introduced into the cylinder will be advanced simultaneously with the lifting of the same.

Attached to the shelves 22 and extending laterally from the surfaces 27 into the direction of the rotation of the drum are the ramp sections 29. These ramps 29 lift up and drop the large pieces over the shelves 22 to avoid carrying them to the top of the drum 10. Thus there is a controlled reduction of the large pieces of extraneous material with less mechanical strain on the breaker. As seen in Fig. 2 the ramps 29 are wedge-shaped with the large ends adjacent to the shelves 22 and thus provide an inclined approach to the surfaces 27 as the shelves 22 move into the material to be lifted. As illustrated in Fig. 1, each inclined surface 27 is provided with two ramps 29 which are arranged at an angle to the radial plane of the drum 10 so as to progressively divert the treated material toward the discharge end. The distance between the ramps 29 is controlled by the size of the pieces of material it is desired to slide over the lifting shelves. The ramps illustrated in Figs. 1 and 2 have a surface 31 which makes an acute angle with the surface 43 of the screen plate sections 21. Pieces of material in the drum 10 large enough to extend from one ramp to the next are lifted off the surface 43 of the plate sections 21 as the rotation of the drum 10 moves the material collected at the bottom toward the lifting shelves 22. The smaller pieces are caught against the shelves 22 and lifted from the screen plate sections 21 on the surfaces 27 while the larger pieces ride up on the ramps 29 upon the rotation of the drum 10. The large pieces rolling or sliding off the ramp members 29 drop toward the bottom of the drum 10 after having been lifted only a fraction of the total lift. The point in the ascension of the

ramp members 29 at which the large pieces spill off is determined by the size of the angle the inclined surfaces 31 makes with the surface 27 of the shelf. As this angle approaches 90° the ramp surface 31 spills off at progressively lower points in the rotation of the drum 10 the large pieces which fall onto the surface 43 of the plate section immediately following. As shown in the sector II of Fig. 2 the surface 43 of the following plate section 21 has started ascending when it receives the pieces from the ramp members 29. The pieces, therefore, do not fall flat against a perpendicular surface when they fall onto the following surface 43 but strike a tilted surface with a glancing blow. As the angle that the pieces strike the surface 43 is removed from the perpendicular so the shock to the drum 10 is reduced. Also the rolling of the large pieces off the ramp members provides a rotational movement which reduces the blow against the surface 43 when the pieces strike the plate sections.

The lifting shelves 22 do not extend over the circumferential screen plate sections 21 adjacent the feed end cone 11. This shelfless reception zone 32 of the drum 10 acts as a rotary screen for removing the slack coal fed in and eliminates the necessity of preliminarily passing the feed over a shaking screen to remove fines and other slack coal. The discharge end of the drum 10 is provided with a plow 34 comprising an imperforate plate formed with a scoop face 33 for picking up the refuse and passing it onto a shoulder 35 from which the discharged material cascades through the discharge opening 36.

The ramp section 29 may be adjustable so that the angle made by its longitudinal dimension with the radial plane of drum 10 may be varied. A modification of this type is shown in the ramp and shelf structure of Fig. 3. The ramp sections 29a are fastened to the screen plate sections 21a by a pin 37 at the apex of the wedge-shaped ramp 29a. The ramp 29a is free to pivot on this pin 37 and is fastened to the shelf section 22a by a bolt 38 attached to a lug 39 which extends over the top of the shelf 22 at the large end of the ramp 29. A nut 41 on the bolt 38 may be tightened to secure the ramp section 29 in place. The pivoting of the ramp section 29 is limited by a slot 42 in which the bolt 38 slides. The slot 42 is fashioned in a lip extending from the rear of the upright flanged portion 26 of the lifting shelf 22. The slot 42 describes the arc of a sector with the pivot pin 37 as the vertex and the ramp section 29 as the radius. Thus the ramp section 29 may be varied in position over the sector described by the slot 42.

In the operation of this device the material to be treated is introduced from the left side of the drum 10 as seen in Fig. 1. The material is fed into the feed cone 11 while the drum 10 rotates. The material to be treated will include the substance to be reduced and cleaned together with any foreign material which should be separated out, as for example, run-of-the-mine coal together with the extraneous rock mined with the coal and tramp iron or pieces of wood picked up in the mining and transportation. The unprocessed material is rumbled in the rotating drum on the screen plate sections 21 of the reception zone 32 thus removing the slack coal which passes through the screen openings 24. A deflector 23 in the reception zone 32 urges the coal and rock to the right into the path of the shelves 22 which bite into the edge of the mass of material. With the rotation of the drum

10 the smaller pieces are caught on the surfaces 27 and lifted upward while the larger pieces ride up on the ramps 29. The large pieces are hoisted over the shelves 22 as soon as the rotation of the drum 10 has tilted the ramp surfaces 31 backward and downward and the large pieces fall a short distance to the surface 43 of the screen plate sections 21. The smaller pieces on the other hand are carried to the top of the drum by shelves 22 and slide off the surfaces 27 to fall back onto the screen plates 21 with consequent fracture and reduction. The large pieces of rock are harder than the coal and resist the falls from the low height at which they are dumped off the ramp surfaces 31 and are urged intact toward the discharge cone 12 by the angle of the ramp sections 29 and the inclined shelf surfaces 27. The scoop face 33 picks up the extraneous material which does not pass through the apertures 24 in the plate sections 21 and lifts it out of the drum through discharge opening 36.

This invention provides an apparatus for assisting in the crushing art in the separation of different material in the crushed material and 25 reducing the wear on the crushing machines. For example, in mining coal it has become a practice to load coal by automatic loading machinery. This automatic loading machinery loads out seams of rock, binder and other foreign material with the coal. This throws a greater load on the separation of the high ash material and foreign matter from the coal. "Bradford" breakers are used in processing the coal both to reduce the size of the lumps of coal to predetermined 30 sizes and also in cleaning the coal. The coal loaded by automatic loading machinery contains among other foreign material large pieces of extraneous rock. This rock is heavier than coal and also harder to break. As it is desired to separate the extraneous matter from the coal the cleaning of the coal may be effected quickest by minimizing the fracture of the rock so that large pieces of rock may be easily removed from the drum 10. The reduction of the degree of fracture of the rock also lessens the amount of strain 35 placed upon parts of the breaker drum 10.

In this invention the lifting of the rock is held at a minimum by the ramp sections which precede the lifting shelves. These ramp sections can be set to select out pieces of rock above a predetermined size and lift these pieces over the lifting shelf so that they will not be lifted up and dropped from a point high in the drum. The large pieces of coal on the other hand will not be continually slid over the shelves as are the large pieces of rock. The pieces of coal being softer than the rock break as they are slid off the ramp sections 29 and fall over the lifting shelves 22. Consequently the coal is rapidly reduced while the rock remains intact. The ramp sections in preserving the extraneous rock in large pieces facilitate the removal of the large pieces of rock from the drum 10 and thereby aid in the separation of the coal and the rock. Thus, the ramp sections serve to both clean and break the coal.

The ramp sections are shown extending only a third of the distance to the next adjacent preceding shelf section 22. The deflecting property 70 of the ramp sections may be emphasized to produce a more definite screw action by extending some or all of the ramp sections forward to the next adjacent shelf. The spacing between the ramp sections may also be adjusted to vary the size of the pieces that are passed over the shelf

sections with the closer spacing passing over smaller pieces.

The angle made by the ramp surfaces 31 with the screen plate section surfaces 43 determines the point in the rotation of the drum 10 that the over-size pieces are slid over the shelf sections 22. By varying the angle of the ramp surface with the screen plate surface the distance of the fall of the over-size pieces also may be varied. The height of the point in the drum 10 at which the over-size pieces slide over the shelf section 22 and off the ramp sections 29 is in a direct ratio with the size of the angle of the ramp surface 31 and the breaker plate surface 43. The greater the angle the higher is the sliding point. By this improved construction a means is provided for advancing material such as coal mined with automatic loading machinery which contains rocks, binder and other foreign material indiscriminately and avoiding the excess wear that handling such material places on breaker machinery.

It will be apparent to those skilled in the art that various modifications can be made without departing from the principles of the invention as disclosed herein and for that reason it is not intended that it should be limited other than by the scope of the appended claims.

Having thus described the invention what is claimed is:

1. In a crushing apparatus for material containing pieces of various sizes a combination with a rotary drum of generally circular form in section and having a peripheral screen, of inwardly projecting shelves extending longitudinally of the inner surface of said screen in position to lift pieces of said material and drop them into the bottom of the screen during the rotation of the drum, and a plurality of series of axially spaced ramp members between said shelves and alternating therewith, said ramp members being of generally triangular shape extending inward from the peripheral screen and having inner surfaces inclined to the surface of said screen to be near said screen surface at their forward ends remote from the following shelves and spaced relatively great distances from said screen surface at

their other ends adjacent said following shelves so as to engage and lift relatively large pieces of material between said shelves and drop said large pieces back into the bottom of the drum as soon as the rotation of the drum has tilted the respective inner ramp surface backward and downward and before the smaller pieces of material are discharged from the corresponding following shelf.

- 10 2. Crushing apparatus as set forth in claim 1 in which a series of surfaces with inwardly projecting shelves are positioned at an angle to the radial plane of the drum and the ramp members are inclined relative to planes normal to the axes of the drum so as to follow the direction of the progress of the material through the drum.
- 15 3. Crushing apparatus as set forth in claim 1 in which the ramp members are angularly adjustable in relation to planes normal to the axes of the drum independently of the shelves.
- 20 4. Crushing apparatus as set forth in claim 1 in which the ramp members have extensions overlying and releasably engaging the inner edges of the shelves.
- 25 5. Crushing apparatus as set forth in claim 1 in which the ramp members have lug members releasably fastened to said shelves to permit angular adjustment to a position other than perpendicular to the longitudinal dimension of said shelves.
